CLAIM

The ornamental design for the product box, as shown and described.

DESCRIPTION

FIG. 1 is a perspective view of a product box showing a first embodiment of our new design;

FIG. 2 is a front view thereof;

FIG. 3 is a rear view thereof;

FIG. 4 is a top view thereof, the bottom view being a mirror image of the top view; and

FIG. 5 is a left side view thereof, the right side view being a mirror image of the left side view.

FIG. 6 is a perspective view of a product box showing a second embodiment of our new design;

FIG. 7 is a front view thereof;

FIG. 8 is a rear view thereof;

FIG. 9 is a top view thereof, the bottom view being a mirror image of the top view; and

FIG. 10 is a left side view thereof, the right side view being a mirror image of the left side view.

FIG. 11 is a perspective view of a product box showing a third embodiment of our new design;

FIG. 12 is a front view thereof;

FIG. 13 is a rear view thereof;

FIG. 14 is a top view thereof, the bottom view being a mirror image of the top view; and,

FIG. 15 is a left side view thereof, the right side view being a mirror image of the left side view.

While one surface of the product box is transparent, the interior of the product box is not shown through the transparent surface because it forms no part of the claimed design.

The broken lines in the drawing represent portions of the product box that form no part of the claimed design.
